UNITED STATES PATENT OFFICE.

WILLIAM AUGUSTUS LEGGO, OF MONTREAL, QUEBEC, CANADA, ASSIGNOR
TO JACKSON RAE AND JAMES CRADOCK SIMPSON, BOTH OF SAME PLACE.

TELEGRAPHIC ALPHABET.

SPECIFICATION forming part of Letters Patent No. 364,356, dated June 7, 1887.

Application filed June 26, 1886. Serial No. 206,362. (No model.)

To all whom it may concern:

Be it known that I, WILLIAM AUGUSTUS LEGGO, of the city of Montreal, in the district of Montreal and Province of Quebec, Canada, have invented certain new and useful Improvements in Telegraphic Alphabets; and I do hereby declare that the following is a full, clear, and exact description of the same.

My invention consists in so framing the telegraphic alphabet that the characters indicating the several letters shall be composed of one kind of mark or sign only, the difference in the characters indicating the letters being marked by the grouping together and inter-spacing of these several signs.

As all marks, whatever may be their relative length, have the same significance, no error can arise from the confusion of the dots and dashes of the European Morse code or the dots, dashes, and spaces of the American Morse system. It has been found in practice in these systems, and specially in their use in automatic telegraphy, that the sign preceding a break becomes to some extent prolonged, and in the case of a dot may easily be mistaken for a dash, thus rendering the work unintelligible, and it is to remedy this defect, among others, that this alphabet is designed.

I propose to divide up the letters of the alphabet into groups, each group being denoted by a distinct sign or combination common to all the letters of its group. For instance, the first group would be indicated by a single mark, the second by two marks, and so on. Each letter of the group will be indicated by a distinct or specific sign or combination—such as one mark for the first, two marks for the second, &c.—the sign indicating the letter being always separated from that showing the

group by a defined space and being common to all the groups.

In the accompanying drawings, forming part of this specification, I show, in Figure 1, an alphabet in which the letters are divided up into six groups, five consisting of five letters each, and the last of the letter Z and sign &. Fig. 2 represents the numeral and stop signs.

Thus the letter D, being the fourth of the first group, will be shown by one mark, then a space, and then four marks, the one mark being the sign of the group and the four marks the number of the letter in it. The letter K, being the first of the third group, is shown by three marks, a space, and then one mark; and T, being the last letter of the fourth group, has four marks, a space, and then five marks.

The numerals, understood also as stops or signs, are as shown in Fig. 2.

I am aware that in the English Patent No. 691 of 1877 a telegraphic alphabet or code of signals is shown, consisting in one modification of "dots combined with spaces;" but in this case it is also clearly stated that the marks are produced "alternately in two parallel lines." I therefore disclaim this arrangement, what I claim being as follows:

A telegraphic alphabet or code consisting of groups representing groups of letters of the ordinary alphabet, with different signs for each group, the several group-signs being common to all the letters of these several groups, and with specific letter-signs for each letter of a group, the letter-signs being common to all the groups, substantially as described.

WILLIAM AUGUSTUS LEGGO.
